ARMATURE BAND, APPLIED TO END-URNS OF WOUND ROTORS OF DYNAMO-ELECTRIC MACHINES, AND PROCESS OF APPLYING THE SAME

UNITED STATES PATENT OFFICE

2,397,187

BAND FOR ARMATURES

Clarence Lynn, Pittsburgh, Pa., assignor to Westinghouse Electric Corporation, East Pittsburgh, Pa., a corporation of Pennsylvania

Application October 13, 1943, Serial No. 506,054

2 Claims. (Cl. 24—27)

My invention relates to single-layer wire bands for resisting the centrifugal force on the end-turns of wound rotors of dynamo-electric machines. Since the earliest days of this art, failures of such bands have usually occurred by shearing of the solder holding the turns together, and by the end of the band pulling through the clip which holds the band. Practically no bands have failed, heretofore, by actual fracture of the banding-wire itself, until, of course, failure of the band had started by solder-failure, after which the entire band was usually destroyed.

The object of my invention is to provide a single-layer band, and a new method of applying a single-layer band, or a multiple-layer band, which overcomes this difficulty and requires sufficient force to cause the wire itself to fail before the band will fail.

In the drawing, Fig. 1 is a fragmentary longitudinal sectional view of a portion of a direct-current dynamo-electric machine, showing a band applied on one end of the armature, and Fig. 2 is a developed view of the band, showing its manner of construction in accordance with my invention.

My invention is of general application in any place where it is necessary to secure an end of a wrapping-wire to the wire itself, without joining one end of the wire to the other end. As shown in Fig. 1, the invention is illustrated in application to the armature or rotor-member 3 of a direct-current dynamo-electric machine which also has a field-member or stator-member 4. The invention relates to a banding-wire 5 which is applied, in a single layer, about the periphery of the coil-ends or end-turns 6 of the armature-winding, to retain the winding against centrifugal force. In the particular case illustrated, the band 5 is used to hold the end turns 6 against a coil-support 7, with an insulating spacer 8 inserted between the upper and lower conductors, and with an insulating layer 9 disposed under the band 5.

The manner of applying the band 5 is illustrated in Fig. 2. An intermediate one-hundred-eighty-degree starting-loop 10 is first formed near one end of the wire, and the short end 11 of the wire is then wrapped once around the end-turns 6 of Fig. 1, after first inserting a number of flattened-out clips 12 under the place where the finished band 5 is to lie, the ends 13 of the clips being flat, as indicated by construction-lines for one of the clips 12. When the short end 11 has passed once around the circumference, passing downwardly from its starting-loop 10, and coming back downwardly from the top of Fig. 2 after passing once

around the circumference, completing an end-turn of the banding-wire, the wire-end of this end-turn is then looped tightly in an interlocking loop through the starting-loop 10, which may conveniently be done by marking off the point 14 where the interlocking loop is to be made, making a sharp bend of nearly ninety degrees at this point, leaving a straight end 15 sticking out, which is then threaded through the loop 10, pulled tight, and bent or looped back on itself, as indicated at 15', and temporarily fastened, or held, in any convenient manner (not shown).

The long end of the wire from the starting-loop 10 is then wrapped tightly, in a single layer 15, of as many turns as may be desired, around the periphery of the armature end-winding 6 (or other object is to be bound). As shown in Fig. 2, this long wire-end is shown at 16, and is wrapped in the direction of the arrow, passing downwardly 20 from the loop 10, and coming back downwardly from the top of Fig. 2 after passing once around the circumference, and then continuing on around and around, in a plurality of turns lying side-by-side around the circumference, until the 25 last of this series of turns is reached, as indicated at 37. At a point preferably about 180° displaced from the starting-loop 10, an intermediate one-hundred-eighty-degree loop 38 is then formed in the wire of the turn 37, and the short, remaining 30 wire-end 39 is wrapped around the end-turns 6 (Fig. 1) of the armature-winding, being doubled back alongside of the turn 37 and going once around, in the opposite direction as shown by the arrows on this end-turn 39, in Fig. 2. At the 35 point 40 where this wire-end 39 comes back to the intermediate loop 38, a sharp bend of nearly ninety degrees is made, providing a straight, laterally projecting end 41, which is threaded through said intermediate loop 38, pulled tight, and bent or 40 doubled back against the end-turn 39, as shown at 41', so as to provide an interlocking loop or joint with the intermediate loop 38.

The starting-end 15' is then (or at any intermediate time), cut off and secured in place, and the finish-end 41' is likewise secured in place, by bending over the ends 13 of the several clips 12, so as to lie flat against two or three turns of the band 5, as indicated at 13', and the finished band is then held together by an application of solder 50 42, as in the prior art.

I claim as my invention:

1. A banding-wire having a plurality of turns lying side-by-side around an object to be bound, characterized by having an end-turn, at at least one end of the banding-wire, passing around the

object in the direction opposite to the next adjacent turn, said banding-wire having an intermediate loop at the place where said end-turn doubles back alongside of said next adjacent turn, the wire-end of said end-turn being threaded through said intermediate loop and doubled back against itself. 5

2. A banding-wire having an intermediate one-hundred-eighty-degree starting-loop therein, said wire having a short end and a long end extending 10 from said intermediate starting-loop, said short end passing once around the object to be bound, completing an end-turn of the banding-wire, the wire-end of the end-turn being looped through

said intermediate starting-loop, and bent back on itself, said long end passing alongside of said end-turn around the object to be bound, said long end terminating in a second end-turn which passes around the object in the direction opposite to the intermediate portion of said long end of the banding-wire, said long end having a second intermediate loop at the place where said second end-turn doubles back alongside of said intermediate portion, the wire-end of said second end-turn being threaded through said second intermediate loop and doubled back against itself.

CLARENCE LYNN.
